UNITED STATES PATENT OFFICE.

FREDERICK H. BEROLD, OF WYOMING, OHIO.

SHEET-DELIVERING MECHANISM FOR PRINTING-PRESSES.

1,234,122.

Specification of Letters Patent. Patented July 24, 1917.

Application filed October 30, 1916. Serial No. 128,505.

To all whom it may concern:

Be it known that I, FREDERICK H. BEROLD, a citizen of the United States, residing at Wyoming, in the county of Hamilton, 5 State of Ohio, have invented certain new and useful Improvements in Sheet-Delivering Mechanism for Printing-Presses, of which the following is a specification.

My invention relates to sheet delivering 10 mechanism for controlling the action of the sheets in their delivering and dropping movements, and has for its object the provision of novel means whereby the printed sheets are caused to drop in regular manner.

15 Stops are provided in delivering mechanisms to limit the travel of the sheet. Upon contact of the sheet with said stops the sheet is still subject to its inertia of movement imparted during the travel of the 20 sheet in its delivering movement. The difficulty in the dropping of sheets heretofore has been that this inertia of movement caused a crowding of the rear portion upon the front portion of the sheet, resulting in 25 a buckling or cross-folding of the sheet, which resulted in the dropping of the sheet in such buckled or folded condition and prevented the flatwise laying of the sheet upon the pile.

30 It is the object of my invention to avoid these objections, and to stiffen the sheet in the direction of its path of travel so as to resist the folding or buckling action caused by the stoppage of the forward edge of the 35 sheet while the sheet is subject to its inertia of movement, to cause the sheets to stack flat on the delivery stack, and to prevent damage to the front edge of the sheet by contact with the stop.

40 My invention consists in providing novel means whereby the printed sheet during its passage to dropping position has a downward bulge imparted to it, the curvature of which extends crosswise of the path of 45 travel of the sheet in its delivery movement, the hollow of the bulge extending lengthwise of said path of travel, so as to stiffen the sheet in the direction of its path of travel.

50 It is the object of my invention further to provide novel means whereby, in the dropping of the sheet, its middle portion extending lengthwise of its path of travel, is caused to descend first so as to be the 55 first portion which makes impact with the previously piled stack of sheets, the side

portions of the sheet then dropping for contact with the previously piled stack of sheets, progressively from the median portion of the sheet toward its outer side edges, 60 whereby the sheet is caused to lie or arrange itself properly upon the stack without bending or buckling, and pockets of air, which have a tendency to prevent a proper laying of the sheet on the previously piled stack, 65 are avoided.

The invention will be further readily understood from the following description and claims, and from the drawings, in which latter:

70 Figure 1 is a plan view of so much of a printing press as is necessary to illustrate my invention.

Fig. 2 is a side elevation of the same with part of the main frame broken away 75 for better illustration of parts.

Fig. 3 is a longitudinal section of the same taken on the line 3—3 of Fig. 1.

Fig. 4 is an enlarged sectional detail of the same taken on the same section line and 80 showing the grippers about to be tripped.

Fig. 5 is a cross-section taken on the line 5—5 of Fig. 1, showing so much of a printing machine as is necessary to illustrate my improved device.

85 Fig. 6 is a longitudinal section taken in the plane of the line 6—6 of Fig. 7, illustrating the manner in which the sheet is bowed downwardly.

Fig. 7 is a cross-section of the same taken 90 in the plane of the line 7—7 of Fig. 6.

Fig. 8 is a longitudinal section taken in the plane of the line 3—3 of Fig. 1, illustrating a modification of the means for drawing the supporting tape taut.

95 Fig. 9 is a plan view of the same.

Fig. 10 is a detail in cross-section taken in the plane of the line 3—3 of Fig. 1, showing a further modification for drawing the tape taut.

100 Fig. 11 is a cross-section of the same taken on the line 11—11 of Fig. 10; and,

Fig. 12 is a cross-sectional detail on the line 12—12 of Fig. 1, showing the means for securing the sheet stops in place.

105 11 represents the main frame, in which a suitable impression-cylinder, exemplified at 12 as partly broken away, is arranged to be suitably mounted and rotated for performing the printing of the sheet. After the sheet is printed it is arranged to be delivered, exemplified as accomplished by means

of a sprocket-chain delivery comprising sprocket-chains 13, one at each side of the machine, arranged to be received loop-wise about sprocket-wheels 14, 15, of which the 5 sprocket-wheels 15 are idler sprocket-wheels loosely rotating on a shaft 10. The sprocket-chains carry suitable gripper-mechanisms which travel with the chains, exemplified as grippers 16 adjustable crosswise of the 10 machine on a rocker-bar 17, and held in adjusted positions by set-screws 17'. The grippers coat with contact-parts 18, adjustable crosswise of the machine on a bar 19, and held in adjusted positions by set-screws 18'. 15 The bar 19 is at each end rigidly secured to a bearing-part 20. The respective bearing-parts are suitably secured to one of the links of each of the sprocket-chains. The rocker-bar has its ends journaled at 22 in 20 said bearing-parts. Springs 21 urge the grippers into gripping position toward the contact-parts 18.

The rocker-bar has an arm 24 secured thereto, having a roller 25 thereon, arranged 25 to contact a gripper opening cam 26, suitably rigidly positioned, as by being received forkwise about the stationary shaft 10 and secured thereto by a set-bolt 27.

The grippers 16 are released by the gripper-cam 26 proximate to the end of travel 30 of the printed sheet, the forward end of the printed sheet being received under end-guides 31 and against end-stops 32 on slides 34 suitably adjustably secured crosswise of 35 the machine on a cross-bar 33, by means of set-screws 35.

The printed sheet 40 is caused to travel in 40 a delivery movement so as to position the same above a delivery table 41 whereon the sheets are stacked, exemplified by the stack of sheets 42, this delivery movement being accomplished by the gripping of the forward end of the sheet by means of the grippers 16, the sprocket-chains carrying the 45 grippers and the sheet gripped thereby with them in their movement. Proximate to the end of the delivery movement, the grippers are caused to release the sheet, the inertia of movement of the sheet carrying it to the 50 end-stops 32.

In the delivery of sheets heretofore it has been difficult, especially when printing thin sheets, to control the proper dropping of the sheets, the inertia of movement of the sheets 55 causing the sheets to crowd against the end-stops, resulting in the cross-buckling of the sheet, in improper dropping of the sheet, damage to the forward or register-edges of the sheets, and excessive abrasions between 60 the unprinted or lower portion of the sheet being dropped with the wet printed surfaces of the previously dropped sheets.

In order to overcome these objections I provide side supports 43 for the sheet, exemplified as tapes, there being preferably one tape 65

for each side of each sheet being dropped. I have exemplified the sheets as being dropped singly. If the sheets are severed to form a plurality of sheets being dropped simultaneously side by side, the mechanisms 70 may be duplicated accordingly.

The tapes are laterally adjustable to accommodate for the width of the sheet being dropped. The rear end of the tape is exemplified as clamped by means of a clamp 44 to a laterally adjustable block 45 adjustable on a cross-bar 46, and held in adjustable position by means of a set-screw 47. The forward end of the tape is received about a roller 39 supported by a block 48 arranged to be laterally adjusted on the cross-bar 80 33 and to be held in adjusted positions by means of a set-screw 49. For rendering the tape taut I have exemplified the same as looped about the roller and provided with 85 an adjustable buckle 50.

If desired, the forward end of each of the tapes may be looped about the roller and sewed to the main stretch of the tape at 51, and the rear end of the tapes pass over a 90 block 145 and have a weight 52 secured thereto for keeping the tape taut, as exemplified in Figs. 8 and 9. The block is provided with lips 53 for guiding the tape, and the block 145 is adjustable laterally on the 95 cross-bar 46 and arranged to be clamped in adjusted positions by a set-screw 147.

I have in Fig. 10 shown a further modification in which the rear end of the tape is received about a spring-actuated roller 55, having a winding action on the tape by means of a spring 56, the roller being journaled in the block 245, the block being adjustable laterally on the bar 46, and clamped in adjusted position by a set-screw 247. 100

In operation, the side supports or tapes are so arranged as to converge toward the rear for supporting the side edges of the sheet by means of supports which approach each other toward the rear of the sheet, so that the rear lateral edges of the sheet may be held in substantially the plane of movement of the front edge of the sheet being delivered. 110

The front edge of the sheet is supported in stretched relation crosswise of the machine by means of the grippers, which pull the sheet over a cross-piece 57, and over and along the tapes or side-edge supports, for supporting the side-edges of the sheet in rear 115 of the grippers. The action upon the sheet is to cause a sagging of the middle portion of the sheet lengthwise of its path of movement for stiffening the sheet lengthwise of such path and preventing buckling or folding of the sheet cross wise of the sheet upon impact of the front edge of the sheet with the stops in the delivery movement. Upon release of the forward edge of the sheet by the grippers, this forward edge will also 120 125 130

bulge downwardly, induced by the downward bulging of the balance of the sheet, for stiffening the front edge in the direction of its movement, so that when said forward edge strikes the stop, injury to said forward edge is avoided.

The sheet will drop between the supports with its middle portion, which extends lengthwise of its path of movement, in 10 downwardly bulged relation, the sheet being caused to drop in this relation, whereby the bulged portion will first reach the stack of sheets on the delivery table, and the lateral portions of the sheet will arrange themselves 15 progressively from the median portion toward the lateral edges upon the stack for preventing cushions of air under the sheet, which would have a tendency to crease or buckle the sheet, and causing the sheet to 20 arrange itself flat upon the previously formed stack.

Suitable jogger mechanism may if desired be provided. Such mechanism is exemplified as comprising jogger boards 61, 25 62, mounted on slides 63, 64, sliding in guides 65, 66, the guides of the side jogger-boards being mounted on side-bars 67 adjustable laterally on the transverse bars 33, 46, and secured in adjusted positions by 30 means of set-screws 68, 69. The guides 65 are adjustable lengthwise of the side-bars and are held in adjusted positions by means of clamp-screws 70. The guides 66 are adjustable lengthwise of the transverse bars 33, 46, and are held in adjusted positions by 35 means of clamp-screws 71.

Suitable bell-crank levers 74, 75, are pivoted at 76, 77, to the guides 65, 66. They are articulated at 78, 79, respectively with 40 the slides 63, 64, for transferring motion thereto, and are articulated at 80, 81, with blocks 82, 83, adjustably secured by set-screws 85, 86, lengthwise on operating bars 87, 88. The bars 87 are articulated at 45 to arms 91 adjustably secured lengthwise on a rock-shaft 92, the rock-shaft being rocked by means of an arm 93 in suitable manner, as by a reciprocating rod 94. A bell-crank lever 95 transfers motion from one of the 50 operating bars 87 to the operating bar 88.

Suitable fingers 96 adjustable laterally on a rock-shaft 97 act as front stops for the sheets passing to the table 41. The fingers are held in normally depending positions by 55 a spring 98.

Having thus fully described my invention, what I claim as new and desire to secure by Letters Patent is:

1. In sheet delivering mechanism for 60 printing presses, the combination with delivering means acting on the forward edge of the sheet for delivering the sheet, of supports for the side portions of the sheet arranged convergently toward the rear.

65 2. In sheet delivering mechanism for

printing presses, the combination with delivering means acting on the forward edge of the sheet for delivering the sheet, of supports acting solely upon the side portions of the sheet being delivered, and means for 70 adjusting said supports laterally for adjusting the angular relation between said supports, and arranged for dropping the sheet between said supports and retarding the dropping of said side portions. 75

3. In sheet delivering mechanism for printing presses, the combination with delivering means acting on the forward edge of the sheet for delivering the sheet, of supports for the side portions of the sheet arranged convergently toward the rear, and means for adjustably positioning the rear portions of said supports toward and from each other. 80

4. In sheet delivering mechanism for printing presses, the combination with delivering means acting on the forward edge of the sheet for delivering the sheet, of supports acting solely upon the side portions of the sheet being delivered, and means for 90 adjusting said supports laterally for adjusting the angular relation between said supports, constructed and arranged for dropping the sheet between said supports with the dropping of said side-portions retarded, and jogger mechanism acting on the sheet during dropping of the same. 95

5. In sheet delivering mechanism for printing presses, the combination with delivering means acting on the forward edge 100 of the sheet for delivering the sheet, of flexible supports for the side portions of the sheet, means for adjustably positioning the rear portions of said supports toward and from each other, and means for applying tension to said flexible supports. 105

6. In sheet delivering mechanism for printing presses, the combination, with delivering means acting on the forward edge of the sheet for delivering the sheet, of supports for the side portions of the sheet extending in converging lines, converging toward the rear, and over which said side portions of the sheet travel in the delivering movement of the sheet for being supported by said supports, and past which said side portions of the sheet pass upon release of the sheet by said delivering means. 110

7. In sheet delivering mechanism for printing presses, the combination, with delivering means acting on the forward edge of the sheet for delivering the sheet with said forward edge in a substantially straight line, of supports for the side portions of the sheet, said supports relatively converging 115 toward the rear, the side portions of the sheet arranged to travel upon said supports in the delivering movement of the sheet for being supported by said supports in said delivering movement, with the middle portion 120

125

130

tion of the sheet in rear of its front edge formed with a downward bulge extending lengthwise of the path of movement of the sheet and having a curvature extending crosswise of said path, and said side portions of the sheet arranged to drop past said supports upon cessation of said delivering movement of the sheet.

8. In sheet delivering mechanism for printing presses, the combination, with delivering means acting on the forward edge of the sheet for delivering the sheet with said front edge in substantially a straight line, of supports for the side portions of the sheet, said side portions of the sheet arranged to travel upon said supports in the delivering movement of the sheet for being supported by said supports in said deliver-

ing movement, with the middle portion of the sheet in rear of its front edge 20 formed with a downward bulge extending lengthwise of the path of movement of the sheet and having a curvature extending crosswise of said path, said side portions of the sheet arranged to drop past said supports upon cessation of said delivering movement of the sheet and to follow said bulged portion into dropped position.

In testimony whereof, I have hereunto signed my name in the presence of two subscribing witnesses.

FREDERICK H. BEROLD.
